UNITED STATES PATENT OFFICE.

JOSEPH R. WILKINSON, ENOCH A. BARNARD, AND LIONEL E. BOOTH, OF ANACONDA, MONTANA, ASSIGNORS OF FORTY-TWO AND ONE-HALF PER CENT TO SAID WILKINSON, FORTY-TWO AND ONE-HALF PER CENT TO SAID BARNARD, AND FIFTEEN PER CENT TO SAID BOOTH.

DEWATERING AND SETTLING TANK FEEDER.

Application filed May 25, 1917. Serial No. 170,940.

To all whom it may concern:

Be it known that we, JOSEPH R. WILKINSON, ENOCH A. BARNARD, and LIONEL E. BOOTH, citizens of the United States, residing at Anaconda, in the county of Deerlodge and State of Montana, have invented certain new and useful Improvements in Dewatering and Settling Tank Feeders, of which the following is a specification.

10 In the concentration of ores by flotation, the pulp coming from the flotation-cells contains a certain amount of gas which interferes with the subsequent recovery of the solids of the pulp. It is the present practice to send the flotation-cell-product to dewatering and settling-tanks to facilitate the recovery of the valuable contents of the pulp. Experience has shown that in the operation of settling-tanks the formation of froth on 15 the surface of the liquid therein is a constant source of trouble and expense, interferes with the control of the feed, and that an efficient settling of the solids is prevented.

It is the object of this invention to provide a method of and apparatus for feeding dewatering and settling-tanks which will avoid the occurrence of froth upon the surface of the liquid in the settling-tanks and allow of absolute control of the feed-volume.

30 The method hereinafter described for removing the froth comprises, briefly, the introduction into the system of a reservoir or reservoirs into which the pulp on its way to the settling-tanks is led, and wherein the entrained air or gas is removed. The degasified pulp is then conveyed into the settling-tanks to a point beneath the surface of 35 the liquid therein.

The preferred apparatus for carrying out 40 the operation is shown in the accompanying drawings, in which—

Figure 1 is a plan view of a settling-tank in combination with one form of the dewatering and settling-tank reservoir;

45 Figure 2 is a side view of the same, part of the settling-tank being cut away to show the entry of the pulp to a point below the surface of the liquid;

Figure 3 is a plan view of another form 50 of reservoir, the cover being removed;

Figure 4 is a side view of the same, partly in section, the cover being attached;

Figure 5 is a plan view showing a froth-

removing reservoir similar to that shown in Figs. 3 and 4 delivering pulp to a unit of 55 six settling-tanks, and

Figure 6 is a sectional view of one of the series of reservoirs intended for the last tank of a series.

As shown in Figures 1 and 2, the apparatus comprises a pulp distributing-launder 1, a gas-removing reservoir 2 which receives the pulp through an inlet 3 from the launder 1, and which is provided with an over-flow opening 4. A switch 10 diverts pulp from 60 the trough 1 into the inlet 3. A pipe 5 connected to the bottom of the reservoir 2 and provided with a flow-control valve 5' serves to convey the degasified pulp 6 from such reservoir to a point beneath the operating- 65 level of a settling-tank 7. The latter may rest upon suitable supports 8, and a platform 9 is arranged in proximity to the apparatus to facilitate inspection and operation. A spreading-baffle 11 is preferably so 70 disposed opposite the outlet of the conducting-pipe 5 as to facilitate spreading of the incoming pulp.

The pulp flowing in the distributing feed-launder 1 enters the reservoir 2 where the 80 gas accompanying the pulp rises to the top due to the hydrostatic pressure in the reservoir. The degasified pulp is then conveyed by the conduit 5 to a point beneath the surface of the pulp 6 in the settling-tank 7 85 where an efficient settling of the solids occurs. By means of the valve 5', the volume of feed to the settling-tank 7 can be readily controlled and this with the assistance of the overflow permits a constant level to be maintained in the reservoir-box 2. The valve 5', 90 which may be a gate-valve, is so manipulated that there will be an overflow at all times. The froth accompanying the pulp and the excess pulp flows back, of course, into the 95 launder and on to the next tank of the series until the end tank is reached, where the froth is finally broken down by a fine spray, as hereinafter more fully described.

As shown in Figures 3, 4 and 5, the apparatus comprises a central froth-removing reservoir 12 provided with a cover 13 and having partitions 14, 15, 16, 17 and 18 dividing the reservoir into a series of compartments 19, 20, 21, 22, 23 and 24. A feed-launder 25 supplies the pulp to a distribut- 100 105

ing-launder 26 from which the pulp passes into the respective compartments through inlets 27, 28, 29, 30, 31 and 32, being effectively diverted thereto by switch-plates 33, 34, 35, 36, 37 and 38, respectively. Delivery pipes 39, 40, 41, 42, 43 and 44, fitted at convenient points with suitable valves 39', 40', 41', 42', 43' and 44', convey the degasified pulp to the battery of settling-tanks 45, 46, 47, 48, 49 and 50, to a point beneath the operating-level of the pulp in each tank. The top edges of the partitions 14, 15, 16, 17 and 18 are somewhat below the lowest point of the distributing-launder 26, so that above 15 the partitions there is free communication between the several compartments.

The operation as carried out in this arrangement is as follows: The pulp coming from the main feed-reservoir 25 enters the 20 distributing-launder 26 passing through feed-inlets 27, 28, 29, 30, 31 and 32 to compartments 19, 20 21, 22, 23 and 24 of the central reservoir 12. The gas contained in the pulp, due to the hydrostatic pressure in 25 the reservoir, rises to the top and the degasified pulp passes by the valved conduits 39, 40, 41, 42, 43 and 44 to a point beneath the operating-level of the liquid in each settling-tank, where efficient settling occurs.

30 The last of the series of reservoirs is equipped as shown in Figures 4 and 6, with automatic-valve-mechanism 55, to maintain under normal working conditions a constant pulp-level in the reservoir, this being necessary because of the variation in the volume of the feed. This valve-mechanism, operating similarly to well known float-controlled-valves, is composed of a float 56 which rests on the surface of the liquid and 35 controls the cone-valve 57. Since above the partitions 14, 15, 16, 17 and 18 the pulp can flow freely from one compartment to another, it will be apparent that the excess pulp will be carried to the end compartment 40 45 24 and cared for by the automatically operated valve 57. The gate valves regulating the flow of feed from the respective reservoir-compartments are kept sufficiently closed to keep the pulp level above the top

of the compartment partitions, and insure a 50 flow towards the float and valve compartments. A spray of water 24^a, Figure 6, is placed over the float in the end-tank to break down any troublesome froth.

The introduction of the pulp into the reservoir before its entry into the settling-tank may eliminate all the gas from the pulp or it may eliminate the greater part, the remaining part being light and non-troublesome. The degree of elimination of the gas 60 from the pulp is determined by the requirements of the plant and is controlled by the size and shape of the reservoir.

It is obvious that a central reservoir may serve a battery consisting of any number 65 of settling-tanks, a unit of six having been taken, as shown in Figure 5, merely for the purpose of illustration.

We claim:—

1. In apparatus for ore concentration, the 70 combination of a plurality of settling tanks and apparatus for feeding pulp thereto free of gases by means of hydrostatic pressure, said means comprising a vessel and partitions for dividing it into a plurality of compartments, the said partitions terminating below the upper edge of the vessel, means for distributing the pulp into said compartments, an outlet at the bottom of each compartment, means for normally maintaining 80 in one of the compartments a substantially constant level, means for regulating the ratio of flow of pulp into the other compartments and the flow out through the outlets at the bottom to maintain an overflow of 85 pulp into the constant level compartment from the other compartments and connections between the different outlets and the different settling tanks.

2. Apparatus according to claim 2 including 90 means operative to destroy the froth in the constant level compartment.

In testimony whereof, we affix our signatures.

JOSEPH R. WILKINSON.
ENOCH A. BARNARD.
LIONEL E. BOOTH.
